CLAIM

I claim the ornamental design for a dog collar with fixed D-ring, as shown and described.

DESCRIPTION

FIG. 1 is a front isometric view of a dog collar with fixed D-ring showing my new design;

FIG. 2 is a rear isometric view thereof;

FIG. 3 is a front elevation view thereof;

FIG. 4 is a right side elevation view thereof;

FIG. 5 is a top plan view thereof; and,

FIG. 6 is a bottom plan view thereof.

The broken lines showing collar adjusters and a fastener is for the purpose of illustrating portions of the article that form no part of the claimed design.
